Attorney.

UNITED STATES PATENT OFFICE.

JOHN F. KINGWILL, OF CHICAGO, ILLINOIS.

DOUBLE-POINTED TACK-SORTING MACHINE.

SPECIFICATION forming part of Letters Patent No. 354,909, dated December 28, 1886.

Application filed April 26, 1886. Serial No. 200,184. (No model.)

To all whom it may concern:

Be it known that I, JOHN F. KINGWILL, a citizen of the United States, residing at Chicago, Cook county, Illinois, have invented certain new and useful Improvements in Tack-Sorting Machines, of which the following is a specification.

My invention relates to machines designed to receive quantities of double-pointed tacks in bulk, and then to automatically sort and straighten them up and run them into columns of tacks to be packed, or to be delivered in a proper position to a tack-driving machine.

15 The object of my invention is to provide a machine which shall automatically accomplish the above result, requiring only to be supplied with a sufficient quantity of tacks. This object I attain by the mechanism illustrated in the accompanying drawings.

Figure 1 is a section of my device secured on a driving-frame of a tack-machine. Fig. 2 is a side view of the same. Fig. 3 is a plan section of same.

25 Like parts are indicated by the same letter in all the figures.

A A are the vertical frame-pieces; B B and C, the cross-pieces; E, an upper elevated inclined tack-chute; F F, the side pieces of an 30 oppositely-inclined sorting frame or riddle; G, a cross-head in the riddle supported on the rod G'. H is the riddle-box; I I I, tacks shown in various positions; J, the tack-driving head of a tack-machine, shown in these 35 drawings only to illustrate the use to which my device may be put.

K is a counter-shaft driven in the usual manner and carrying a crank wheel, L.

The bottom of the sorting frame or riddle 40 is formed of the ways or guides or bars M M, having parallel upper ends, M' M'. N N are continuations of these ways. The ways and continuations thereof are arranged so as to form a frame of closely-set parallel narrow 45 bars, which gradually increase in diameter, diverge, and finally curve at the lower ends, so as to properly deliver the tacks.

O is a door in the side of the riddle-box. P is a spring which engages the rod G', and 50 R is a lug on the rod S, which is jointed at T and secured to the crank-wheel L. As the rod reciprocates, the spring and lug operate to agitate the cross-head in the riddle, and

thus also agitate the tacks which may be lying on the bars in the same.

The operation of my machine is sufficiently 55 illustrated. The tacks are taken from the riddle-box and put into the chute, where they fall on the parallel ends of the riddle-bars. Here they are agitated as described, and they 60 gradually straddle the bars in a tangled and mixed condition. The bars are placed so near together that but a small portion of the tacks will fall to the bottom of the box below. The 65 tacks which have straddled the bars are gradually worked downward along the bars by their agitation until they reach the point where the bars begin to diverge. Here they are separated from each other and somewhat relieved from their tangled condition. All 70 tacks which may have been riding on top of the bars are dropped between them to the bottom of the box below. As the tacks pass 75 down onto the enlarged ends of the ways or bars they are straightened up until they reach the point where the width of the bars is nearly equal to the space between the sides of the tacks, where they will be found to be thoroughly straightened up and arranged in continuous even rows of tacks on the bars. They 80 may then be delivered into a driving-machine, as suggested and partly illustrated, or they may be strung or boxed in regular order for shipment.

I claim and desire to secure by Letters Patent—

1. A tack-sorting machine consisting of an elevated delivery-chute, a lower receiving-box, and an intermediate riddle composed of bars arranged to be agitated.

2. In a tack-sorting machine, a riddle composed of thin parallel and diverging bars.

3. In a tack-sorting machine, a riddle consisting of thin parallel and diverging inclined bars.

4. In a tack-sorting machine, a riddle consisting of a series of thin inclined parallel and diverging bars which gradually increase in diameter.

5. In a tack-sorting machine, a riddle consisting of a series of inclined ways which gradually diverge and increase in diameter toward their lower ends.

Witnesses: JOHN F. KINGWILL,
FRANCIS W. PARKER,
CHAS. S. BURTON.
